UNITED STATES PATENT OFFICE.

GUILLAUME WEBER, OF HAYANGE, FRANCE, ASSIGNOR TO SOCIETE LES PETITS FILS
DE FRANCOIS DE WENDEL ET CIE., OF PARIS, FRANCE.

BLASTING CARTRIDGE.

Application filed September 27, 1919. Serial No. 326,977.

To all whom it may concern:

Be it known that I, GUILLAUME WEBER, citizen of the Republic of France, residing at Hayange, Lorraine, France, have invented new and useful Improvements in Blast Cartridges, of which the following is a specification.

It is well known that hydrocarbons have no absorbing power or a very low absorbing power for liquid air and in manufacturing liquid air blast cartridges, said hydrocarbons were heretofore mixed with an absorbing substance capable of absorbing several times its own weight of liquid air and keeping it for a certain time. Among such absorbing substances are kieselguhr, soot, cork flour, etc. Some of said substances, such as kieselguhr, which act as an inert material have for their effect to decrease the power of the explosive and other substances, such as soot, which act as a combustible absorbent enhance the production of smoke.

This invention consists in a blast cartridge having a watertight envelope which contains hydrocarbons, and liquid air without an addition of an absorbing substance.

In the accompanying drawing, given by way of example:

0 Figs. 1 and 3 are longitudinal sections of two modifications of a blast cartridge constructed in accordance with the invention;

Fig. 2 is a cross section of the same along the line A—B of Fig. 1; and

5 Fig. 4 is a cross section of the same along the line C—D of Fig. 3.

As shown in the drawing, the improved cartridge is composed of a water-tight rigid envelope *a* of cardboard or any similar material which contains a hydrocarbon such as naphthalene as shown at *b* with an addition of combustible metallic powders or not. The envelope is provided with a closing plug *c* having a hole through which the fuse cord *e* may extend. A primer may be provided. A stopper *d* is used to close said hole and provided with a narrow duct *g*,

so that when the liquid air has been introduced the evaporated air only can escape. The hydrocarbon can be enclosed in a 50 satchel or bag of linen *f* or similar material.

The sensitiveness to shock, propulsion or friction, as well as the danger in handling the blast cartridge are reduced to a minimum, by using a rigid envelope of cardboard or any similar material. 55

For the purpose of ensuring a complete combustion of the hydrocarbon, the cartridge may be only partly filled with said material and the proportion of liquid air 60 with respect to the combustible substance may be adjusted so as to give the blast cartridge a greater or lesser duration.

To the hydrocarbon such as naphthalene, paraffin wax or similar materials, in a solid or liquid state, it is advantageous to further add combustible powders of metals or other substances such as aluminium, antimony, magnesium, iron, iron oxide, silicium, silicids, etc., the power of the explosive being 65 thereby considerably augmented without increasing the production of objectionable gases. 70

Having now described my invention what I claim as new and desire to secure by Letters Patent is:

1. A blast cartridge comprising a hydrocarbon, liquid air and a watertight, rigid envelope made of cardboard in which said elements are enclosed without any absorbing 80 substance. 85

2. A blast cartridge comprising a hydrocarbon, combustible powders, liquid air, a watertight envelope made of cardboard in which said elements are enclosed without any absorbing substance. 85

In testimony whereof I have signed my name to this specification in the presence of two subscribing witnesses.

GUILLAUME WEBER.
